UNITED STATES PATENT OFFICE.

JOHN LUMSDEN, OF OTTAWA, ONTARIO, CANADA.

PEAT DRIER AND THE LIKE.

Application filed December 6, 1921. Serial No. 520,368.

To all whom it may concern:

Be it known that I, JOHN LUMSDEN, a subject of the King of Great Britain, and resident of the city of Ottawa, in the Province of Ontario and Dominion of Canada, have invented certain new and useful Improvements in Peat Driers and the like, of which the following is a specification.

This invention relates to improvements 10 in peat driers, and the objects of the invention are to provide a new, simple and economical means for effectively drying peat fuel.

A further object is to provide practical 15 means of this character that, in comparison with means heretofore generally recognized and adopted, will give most satisfactory results for much less expenditure.

A still further object is to provide a drier 20 of this character adapted to be used in combination, not only with any well-known method of heating and delivering the air thereto, but also in combination with a new and improved method as herein illustrated, 25 whereby the surplus heated air from a furnace or boiler, which would otherwise be wasted, is here not only conveyed to the drier, but also is tapped on the way to increase its volume and regulate the temperature to meet all requirements.

Another object is to provide a drier of this character that may be used in any suitable position, either singly, in pairs, or in series, with equally satisfactory results.

Another object is to provide a drier of this character in which the heated air is injected 35 at the opposite end to the feed or supply end.

With these and other objects in view, hereinafter more fully described, the invention 40 consists essentially of an improved drier for peat and the like comprising a suitable casing with rotatably mounted spiral beaters or blades therein adapted, in rotation, to lift,

45 carry and sift the material in the drier whereby, in combination with the surplus heated air from a furnace or the like, the peat is dried and discharged therefrom, means for supplying and discharging the 50 drier, means for ejecting the moisture-charged air therefrom, and means for operating the beaters.

Referring to the drawings, in which like 55 characters of reference indicate corresponding parts in each figure, and in which:

Figure 1 is a side elevation of the drier

arranged in connection with a furnace and a second drier.

Figure 2 is a top view.

Figure 3 is an end view.

Figure 4 is a cross-sectional detail of the drier.

In the drawings:

A pair of driers A and B are shown connected respectively to furnace and fan 65 means for supplying the heated air to the drier. These driers are similar in construction and, here shown, arranged in pairs in staggered relationship to one another. They can, however, also be used singly or in 70 series, arranged in any convenient and suitable manner.

The drier A comprises a cylindrical casing 10 with feed and discharge hopper openings 11 and 12 at opposite ends thereof. 13 75 are blades or beaters keyed to the shaft 14 extending through the casing 10 on suitable bearings 15 and 16 and beyond said casing on the supports 17 and 18 to connect through the pulley 19 with the source of power. 20 80 is another pulley on the shaft 14 at the end thereof, belt connected as at 39 to the pulley 21 on the shaft 22 of the drier B.

The beaters or blades 13 are spirally formed at 23, and are provided with wire 85 mesh or netting extensions 24 partially curved at their outer ends 25 in spaced relationship in rotation to the inside of the casing 10.

26 is a suitable fan of any well known construction arranged to force air through connection 27 into the discharge end of the drier A, while 28 is an exhaust pipe for the moisture-laden air after it, as heated air, has been forced through the peat, agitated by means 90 of the rotary beaters 13 within the cylinder or casing 10. 29 is a fan pulley to be connected to the source of power. 30 is a conveyer from the discharge opening 12 of the casing 10. 100

The drier B, instead of being supplied with heated air in any well-known manner and as shown and employed in the case of the drier A, obtains heated air by a new and improved method from the boiler or furnace of the plant, utilizing from this source the surplus air therein by means of the fan and outlets 31 and 32 arranged at the end of the drier proper B in combination with a suitable conduit 33 connected at 34 to the boiler in such manner as to receive therefrom the waste products of combustion. 105 110

This conduit 33 is connected at its outer end through the fan 31 and blower 32 to deliver the furnace heated air to the drier B.

36 is an air inlet in the conduit 33 provided with a suitable closure 37, preferably a sliding door (as shown), whereby the cool air may be taken in to the conduit to increase the volume of the air therein and at the same time to reduce the temperature to a workable degree that will not ignite or cause ignition of the peat in the drier B when said air is forced thereto. 38 is the fan pulley and 28^a an exhaust.

From the foregoing, the operation of my drier will be apparent. With the plant in operation, the moisture-laden peat, having been ground in any well-known manner, is delivered in this case first to the drier B and then preferably by gravity through a conduit 39 to the drier A, and is there again subjected to the action of the rotatable beaters 13 in conjunction with a volume of fan-driven heated air from the opposite end of same. The combined action of the heated air coming in at one end and the agitation of the peat commencing at the other, causes it to be thoroughly and rapidly dried and, in this process of drying, the beaters 13 play a very important part. Being formed with sifting and end-curved extensions they, not only with the beater or upper portion, hammer the peat but, with the extensions thereon, lift it to a certain extent, sift it, and convey it towards the discharge hopper 12. During all the operation, heated air regulated in volume and temperature is steadily supplied.

By thus in my improved method of utilizing the waste or surplus heated air from the furnace in the plant and by forcing it into the opposite end of the drier to that from which the drier is fed, the results obtained in economy of fuel and extraction of moisture from the peat cannot be over-estimated.

45 With regard to the arrangement of the driers as illustrated and described, it should again be mentioned that one drier may be used with most satisfactory results, but, to attain absolute satisfaction and in order to handle a large quantity quickly, it is preferable to use two or more driers, the operation of all being similar, and preferably, under my new method, having the heated air supplied from the boilers in the plant.

55 As many changes could be made in the above construction and many apparently widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

65 1. A drier for peat and the like comprising

ing a cylindrical casing provided with feed and discharge openings, having a plurality of spiral blades with end-curved wire mesh extensions in spaced relationship to the inner surface of said casing, means at one end of the casing communicating with the source of heated air, means for injecting the heated air into the drier, an exhaust for the moisture-laden air, and means for operating the blades in the drier.

2. A peat drier of the character described comprising a cylindrical casing, a plurality of rotatable spiral blades or beaters formed with wire mesh extensions to provide sifting and carrying means thereon in said casing, feed and discharge openings in the casing, means for supplying heated air to the drier, air exhaust means therefor, and means connected to the source of power for operating the drier.

3. A drier of the character described comprising a casing, a plurality of spiral beaters formed with sifting and carrying means thereon rotatably mounted in said casing, feed and discharge openings in the casing, fan and blower means for said casing adapted to supply heated air thereto, air exhaust means for the casing whereby the moisture-laden air is discharged from the drier, conduit means connecting the drier with the source of heated air, and means in said conduit for regulating the volume and temperature of the heated air, and means for operating the drier.

4. A drier of the class described with feed and outlet openings comprising a casing, spiral beaters provided with sifting and carrying means rotatably mounted in said casing and adapted, in rotation, to agitate, sift and discharge the material from the drier, means for supplying and regulating air to the drier, exhaust air means therefor, and operating means therefor.

5. In a drier of the character described and in combination, a plurality of rotatably mounted disintegrators formed with sifting and carrying extensions and means for ejecting air through said disintegrators whereby the material to be dried is disintegrated, means for feeding and discharging said material at opposite ends of the disintegrators, means for supplying and regulating the volume and temperature of said air, air exhaust means and means for operating the disintegrators.

6. A drier of the character described for peat or the like comprising, in combination, a boiler, a cylindrical drier provided with feed and discharge outlets at opposite ends thereof, a plurality of combined beaters and carriers rotatably mounted in said drier, blower and fan means therefor, and conduit means connecting same with the boiler whereby the surplus heated air from the boiler is forced into the drier at the oppo-

site end to the feed, an opening in said conduit provided with shutter means whereby the volume and temperature of the heated air passing therethrough to the drier is regulated, exhaust air pipe for the drier whereby the moisture-laden air is discharged therefrom.

7. The herein described means for drying peat and the like comprising in combination, a furnace, a drier with feed and discharge openings and having rotatably mounted therein a plurality of spiral beaters with sifting and carrying means thereon, conduit means connecting to said furnace and drier whereby the heated air is conveyed to the drier, means in the conduit for regulating the volume and temperature of said air, exhaust means for the drier, and means for operating the beaters therein.

20 8. In a drier of the character described, in combination with air supplying means, a drier provided with feed and discharge

outlets at opposite ends and having a plurality of rotatable beaters and carriers, said drier adapted to receive at one end, the 25 air supply, and at the other end, the material to be dried, means for operating the beaters and for controlling the flow of air, and air exhaust means for the chamber.

9. In a drier of the character described, 30 the combination with a drying chamber provided with feed and discharge means, of a plurality of beaters and carriers provided with sifting extensions operatively mounted in the chamber, means for injecting air 35 into the chamber at a point opposite to said feed means, air exhaust means for the chamber and means for operating the beaters.

In witness whereof I have hereunto set 40 my hand in the presence of a witness.

JOHN LUMSDEN.

Witness:

W. T. CURFS QUIN.
